[57] CLAIM

The ornamental design for an emergency strobe light or similar article, as shown and described.

DESCRIPTION

FIG. 1 is a perspective view of an emergency strobe light or similar article showing our new design;
FIG. 2 is a front elevational view thereof;
FIG. 3 is a top plan view thereof;
FIG. 4 is a bottom plan view thereof;
FIG. 5 is a rear elevational view thereof; and
FIG. 6 is a side elevational view thereof, the other side being a mirror-image thereof.
